United States Patent Office.

JOHN Q. WELCH, OF OSWEGO, OREGON.

Letters Patent No. 68,920, dated September 17, 1867.

IMPROVEMENT IN ROTARY STEAM ENGINES.

The Schedule referred to in these Letters Patent and making part of the same.

TO ALL WHOM IT MAY CONCERN:

Be it known that I, JOHN Q. WELCH, of the city of Oswego, in the county of Clackamas, and State of Oregon, have invented a new and useful Improvement on the Rotary Steam Engine; and do hereby declare that the following is a full, clear, and exact description of the construction and operation of the same, reference being had to the annexed drawings, making a part of this specification, in which—

Figure 1 represents the engine with the covering removed and the gudgeon of the shaft S cut off, showing the slot P in the shaft S. The oblong circle C is so shaped that a cord drawn through the centre of the shaft S will measure an equal distance to any point in the oblong circle C, as described by fig. 1.

Figure 2 shows the engine.

Figure 3 represents the shaft and mortise, and the valve-piston or slide under it, with one of the four or eight pieces of packing removed.

Figure 4 represents the covering or head, as may be seen in fig. 2, at m, showing the escapement g.

At figs. 1 and 2 steam is let in at the feed pipe F, through the narrow aperture y, and turns the valve or piston D, cutting off the steam that escapes at g. The angular gutter from the steam-chest to the piston or spring W is for the purpose of keeping the shaft steam-tight. The steam coming from the steam-chest presses against the spring or piston W. The slide D is packed in the centre of the shaft, as may be seen in the drawing, either with metallic or lint packing, forced down against the slide D by a screw and spring placed in the hollow end of the shaft S, as set forth in the packing of the edges of the slide D.

Claim.

Having thus described my invention, what I claim therein as new, and desire to secure by Letters Patent, is—

The arrangement of the oblong circle C, slot P in the shaft S, slide D, spring W, aperture y, and the escape at g, substantially upon the principle and in the manner as herein set forth.

JOHN Q. WELCH.
